CLAIM

The ornamental design for a combined tape recorder and television set, as shown and described.

DESCRIPTION

FIG. 1 is a front elevational view of a combined video tape recorder and television set showing my new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a rear elevational view thereof;

FIG. 7 is a top, front and right side perspective view thereof;

FIG. 8 is a front elevational view of a second embodiment of the combined video tape recorder and television set shown in FIG. 1;

FIG. 9 is a top, front and right side perspective view of the embodiment disclosed in FIG. 8, the sides not illustrated are identical to the corresponding sides of the first embodiment;

FIG. 10 is a front elevational view of a third embodiment of the combined video tape recorder and television set shown in FIG. 1;

FIG. 11 is a top, front and right side perspective view of the embodiment disclosed in FIG. 10, the sides not illustrated are identical to the corresponding sides of the first embodiment;
